J. WHITE

SHEET DELIVERY MECHANISM

Original Filed July 12, 1919

FIG. 2

FIG. 1

INVENTOR
JOSEPH WHITE,
by Gifford + Bell, ATTYS.

UNITED STATES PATENT OFFICE.

JOSEPH WHITE, OF PISCATAWAY TOWNSHIP, NEW JERSEY; MINNIE E. WHITE ADMINISTRATRIX OF SAID JOSEPH WHITE, DECEASED, ASSIGNOR TO HALL PRINTING PRESS COMPANY, OF DUNELLEN, NEW JERSEY, A CORPORATION OF NEW JERSEY.

SHEET-DELIVERY MECHANISM.

Application filed July 12, 1919, Serial No. 310,515. Renewed January 18, 1923.

To all whom it may concern:

Be it known that I, JOSEPH WHITE, a citizen of the United States, residing at Piscataway Township, State of New Jersey (post-office address, Bound Brook, New Jersey), have invented certain new and useful Improvements in Sheet-Delivery Mechanisms, of which the following is a specification.

10 This invention relates to sheet delivery mechanisms for printing presses or the like. One of the objects of my invention is to provide means by which sheets, when delivered to the ordinary sheet support such as 15 a board or trays, may be held more or less suspended while they are being positioned on the support or pile of paper. With this and other objects in view, my invention consists of certain novel features of construction, combination and arrangement of parts 20 as will be more fully described and pointed out in the appended claims.

In the drawings, Figure 1 is a side elevation of a portion of a delivery mechanism of a form which I have adopted for purposes of illustration and to which my novel apparatus is shown applied; Fig. 2 is a plan view of Figure 1.

For purposes of illustration I have chosen 30 the type of delivery shown in my prior Patent No. 1,211,512, granted January 9, 1917, portions of this delivery mechanism being shown more or less diagrammatically since the details thereof are fully illustrated 35 in my said prior patent.

In the drawings 10 is a sheet carrier of 40 any form having grippers 11. Cooperating with the carrier 10 is a sheet delivery mechanism which in the form illustrated comprises a pair of chains 12, 13 running on sprockets 14, 15 mounted on shafts 16, 17. The shafts 16 and 17 are driven at constant speed and the chains 12, 13 are provided with one or more gripper shafts 18 carrying 45 sheet grippers 19. Beneath the lower part of the path of travel of the grippers 19 is a sheet support or delivery board 20 which preferably is provided with sheet joggers comprising in the form illustrated a front jogger board 21, side jogger boards 22, 22 and a rear jogger board 23.

A sheet from the carrier 10 passes to a set of the grippers 19 on the carrier chains and from thence is carried horizontally over

the board 20 until the head of the sheet is 55 approximately in the position shown in Figure 2 at which point the grippers are open and the sheet is permitted to drop on the board 20 or on the top of the pile of paper which may have accumulated on that board. 60 The jogger boards are moved toward and away from the pile in the usual manner to gently push the sheet into its proper position on the support.

The construction so far described is well 65 known and is substantially that illustrated in my said prior Patent No. 1,211,512, which patent shows a set of grippers to carry a sheet horizontally over a delivery board and joggers which operate to jog the sheet as it 70 is dropped into position.

I have found that as the sheet being delivered drops on the top of the pile it is liable to engage the pile at various points so that the jogging is made difficult because of 75 the adhesion between the sheet to be jogged and the top sheet of the pile. Since the joggers depend merely on a light push on the edges of a sheet it will be obvious that any resistance to such a push will result merely 80 in folding up the edge of the sheet without properly jogging it.

In order to overcome this difficulty I provide a means by which a current of air can be delivered beneath the sheet as it is dropped, so that the sheet will float into position and be jogged at a time when a layer of air is between the sheet and the top of the pile. As one form of such means I have illustrated means for blowing a plurality of currents of air horizontally beneath the sheet as it is dropped to the pile, these air currents being delivered in a direction substantially opposite to that in which the sheet is being carried by the sheet carrier. These air currents are delivered through a pair of pipes 90 95 25 preferably located as shown at the left of Figures 1 and 2.

These currents of air may be continuous but preferably I allow the air to blow only 100 for a short period before the head of the sheet is released by the grippers 19 and cut it off shortly after the time the sheet begins to drop.

It will be seen that as the sheet is carried 105 out horizontally over the board 20 the air from the pipes 25 passes beneath the sheet and tends to keep it separated from the top-

- most sheet of the pile for a period, and until the joggers 20 can operate on it to adjust it to its place. The sheet then gradually settles into its fixed position and the air may remain under it a sufficient time for it to receive a number of pushes from the joggers before the air passes out. In this way it is insured that each sheet will be in proper position.
- 10 While I have illustrated my device in connection with a specific form of delivery mechanism it will be understood that it may be applied to many different forms. While preferably I use joggers in connection with my novel arrangement, it will also be understood that such joggers are not essential, it being beneficial to supply the air currents beneath the sheet when it is desired to drop such sheets into a definite and fixed opening between sheet guides as found on some types of delivery board.
- 15 It will also be understood that while I prefer to deliver the air currents in the direc-

tions illustrated in Figures 1 and 2, other directions may be utilized so long as the presence of air beneath the sheet as it is being dropped, is insured.

I claim:—

1. In a sheet delivery mechanism, a sheet receiving support, sheet engaging devices to engage the head of a sheet and carry it horizontally and to release it when over said support, and means to deliver a current of air horizontally beneath the sheet prior to and at the time of its release by said engaging device.

2. In a sheet delivery mechanism, a sheet receiving support, sheet engaging devices to engage the head of a sheet and carry it horizontally and to release it when over said support, and means to deliver a current of air horizontally in a direction substantially opposite to that of the horizontal motion of the sheet and beneath the sheet as it is released by said engaging means.

JOSEPH WHITE.
